UNITED STATES PATENT OFFICE.

GEORGE P. MITCHELL, OF SHENANDOAH, IOWA.

WINDOW-BLIND.

No. 922,798.

Specification of Letters Patent. Patented May 25, 1909.

Application filed April 25, 1908. Serial No. 429,269.

To all whom it may concern:

Be it known that I, GEORGE P. MITCHELL, a citizen of the United States, residing at Shenandoah, in the county of Page and State of Iowa, have invented a new and useful Window-Blind, of which the following is a specification.

The object of the invention is to provide a blind that shall be capable of ready adjustment to window frames of different widths, and which may be disposed either above the upper or below the lower sash, and which shall be of such construction as to allow free passage of air through a room but at the same time positively preclude the entrance of rain, whereby it will be unnecessary to close the windows during a rain storm, thereby obviating a source of considerable discomfort to the occupants, especially if the storm be of long duration.

Furthermore, it is one of the objects of the invention to render it possible to air a house, an office or any style of building, either public or private, while the tenant is absent, and without subjecting the latter to worry from fear that rain will beat in the windows.

With the above and other objects in view, as will appear as the nature of the invention is better understood, the same consists in the novel construction and combination of parts of a window blind, as will be herein-after fully described and claimed.

In the accompanying drawings forming a part of this specification, and in which like characters of reference indicate corresponding parts, Figure 1 is a view in elevation taken from the front of the blind. Fig. 2 is a view in vertical transverse section, taken on the line 2—2 of Fig. 1, and looking in the direction of the arrow.

The blind comprises two stiles 1 and 2, a plurality of slats 3 carried by the stile 1, a plurality of slats 4 carried by the stile 2, and a keeper 5 secured to the inner terminals of the slats 4.

All of the parts of the blind are, by preference, made of galvanized iron, on account of its strength, and rust-resisting qualities; but any other sheet metal may be utilized for the purpose that may be found applicable thereto.

Each of the stiles 1 and 2 is a trough-like structure, and between the flanges 6 thereof the outer terminals of the slats are secured, as by soldering. In order to render the slats thoroughly effective for preventing en-

trance of rain between them, and also to provide for a stable attachment between them and the flanges 6 of the stiles, the outer edges 7 of the slats are turned downward, and their inner ends 8 are turned upward, and these edge portions will bear squarely against the opposed faces of the flanges 6, as clearly shown in Fig. 2.

The guide 5 has its upper end 9 deflected to lie upon the outer surface of the uppermost of the slats 3, and is thence extended downward and flexed rearward to pass beneath the lowermost slat 4, thence against the rear edges 8 of the slats 4 to which it is soldered, and upward to the upper edge of the blind.

As shown in Fig. 2, the uppermost slats of the sections 3 and 4 have each a vertical extension 10 and 11 respectively in front of 75 which the lower sash rail is adapted to rest, and to the extension 11 the keeper 5 is soldered.

In order to stay the extensions 10 and 11, and also to impart a finished appearance to 80 the article, there is a brace 12 employed in connection with each of the stiles, the edges 12^a of which are downturned and are secured by solder to the inner faces of the front flanges of the stiles and to the extensions 10 and 11 of the slats 3 and 4. As these braces 85 are of the same width as the flanges of the stiles, they will have the appearance of being continuations of the same and will therefore materially add to the mechanical structure of 90 the device.

As a means for limiting the outward movement of the two sections of the blind, the upper and lower slat of the series 3 is provided with an outturned toe 13 which, by 95 contact with the keeper 5, as shown in Fig. 1, will secure the object sought.

The improvements herein defined, while simple in character, will be found thoroughly efficient for the purposes designed, and will 100 result in the production of a durable and inexpensive form of window blind.

I claim:

A blind comprising two sections arranged for sliding movement relative to each other, each section comprising an upright stile and laterally extending slats mounted thereon, the upper slat of each set being provided with a vertical extension; a guide having its upper terminal rigidly attached to the vertical extension of the upper slat of one of the sets, the free terminal of the guide being 105 110 115

carried downward in contact with the rear edges of the slats of both sets, being passed beneath the slats, and thence carried upward in contact with the forward edges of the slats of both sets, the free extremity of the guide being downbent to contact with the upper slat of the other set.

In testimony that I claim the foregoing as my own, I have hereto affixed my signature in the presence of two witnesses.

GEORGE P. MITCHELL.
